UNITED STATES PATENT OFFICE.

HOWARD K. KING, OF PHILADELPHIA, PENNSYLVANIA, ASSIGNOR TO THE CHAMBERS BROTHERS COMPANY, OF PHILADELPHIA, PENNSYLVANIA, A CORPORATION OF PENNSYLVANIA.

PAPER-FOLDING MACHINE.

SPECIFICATION forming part of Letters Patent No. 700,505, dated May 20, 1902.

Application filed August 7, 1899. Serial No. 726,468. (No model.)

To all whom it may concern:

Be it known that I, HOWARD K. KING, a citizen of the United States, residing in the city and county of Philadelphia, in the State of Pennsylvania, have invented certain new and useful Improvements in Paper-Folding Machines, of which the following is a full, clear, and exact description, reference being had to the accompanying drawings.

10 This invention relates to certain improvements in that class of paper-folding machines wherein the sheet is delivered to relatively arranged sets of folding-rollers, and thereby successively folded on predetermined lines, 15 the sheet being transferred from one set of rollers to another by means of carrying-tapes and being delivered from the final folding-rollers to an underlying packing-trough.

My improvements reside in a novel construction and organization of mechanism whereby the previously-folded sheet shall, preparatory to the final folding thereof, be accurately guided and adjusted to a definite position in respect to the final folding-rollers, 25 and also in various features and combinations of parts whereby advantages are gained, as will be hereinafter particularly described and claimed.

In the drawings, Figure 1 is a rear end elevation of a portion of a folding-machine embodying my invention. Fig. 1^a is a vertical section on line *a* of Fig. 1. Fig. 2 is a side elevation thereof, the inclined folding-rollers and their adjuncts being omitted. Fig. 3 is 35 transverse vertical section on a vertical plane between the last folding-rollers. Fig. 4 is a diagram illustrating one of the inclined tapes, &c., which deliver the sheet into position over the last or inclined set of folding-rollers. Fig. 5 is an enlarged plan view of the last or inclined folding-devices and their carrying-frame detached. Fig. 5^a is a section on line *y* *y* of Fig. 5. Fig. 6 is a side elevation of Fig. 5, the supporting-frame being shown in section. Fig. 7 is a view, partially in section, of the inclined sheet-supporting plates, the end stops and mechanism for adjusting the latter with relation to the incoming sheet. Fig. 8 is a partial end elevation of Figs. 5 and 50 6. Fig. 9 is a section as on line 9 9 of Fig. 6.

The machine illustrated in the annexed drawings is of the type known as an "inter-convertible $\frac{2}{15}$ or $\frac{3}{2}$ insetting machine"—that is, its function is to fold a sheet into two signatures of sixteen pages each or into one signature of thirty-two pages, the two portions of the sheet in the latter case being "inset" in imparting the last fold thereto.

1 designates the main supporting-frame of the machine, and 2 the main shaft, which is 60 driven from a suitable source of power. 3 is the first pair of folding-rollers to which the sheets are successively fed, and thereby folded, and 4 is a vibratory folding-blade by means of which the sheets are tucked into 65 the bite of said rollers. These parts are of usual and well-known construction and operation, and therefore need no detailed description herein.

As the sheet of paper passes between the 70 rollers 3 and is folded thereby it is divided in a well-known manner, as by a cutter on one of said rollers, into two portions or sheets, each of which is carried by suitable carrying-tapes 5 (indicated by dotted lines in Fig. 2) 75 over two sets of folding-rollers 6 and 7, respectively, at right angles to the first set and parallel with each other. The folding-rollers 6 are journaled in the frame 1 of the machine and are rotated from the driving-shaft 2, 80 through gears 8 and 9 on said driving-shaft and one of said set of rollers, respectively. The rollers 7 are journaled in the upper part of a frame 10, which is mounted upon the main frame 1 in a manner, as hereinafter described, to permit of the adjustment of said frame 10 and its rollers toward or away from and parallel with the relatively fixed rollers 6. The rollers 7 are rotated from the driving-shaft 2 through gears 11 and 12, carried 90 by said driving-shaft, and one of said rollers, respectively.

Coacting with the folding-rollers 6 to tuck the sheet therebetween is a folding-blade 13, carried by a rock-lever 14, whose movements 95 are controlled by a cam 15 on a suitably-disposed shaft 16, which is journaled in the main frame and geared to the driving-shaft as usual. A folding-blade 17, similar to blade 13, coacts in like manner with the folding- 100

rollers 7. The shaft upon which is mounted the rock-lever 18, carrying the blade 17, is journaled in the adjustable frame, and the cam 19, which effects the requisite movements of said lever, is mounted on the shaft 16, so as to be adjustable longitudinally thereof concurrently with the adjustment of the frame 10, as below described. Journaled in this frame 10 below the plane of the rollers 6 and 7 is a set of rollers 20, the axes of which are inclined to the horizontal at an angle of about fifty degrees, more or less. In this frame, beneath and parallel with the rollers 20, is also journaled a set of rollers 21, that are positively driven from one of the rollers 7 by a gear-train 22. The rollers 21 are geared to the rollers 20, so as to be concertedly driven thereby, one of each set of rollers being provided with a gear-wheel 23, between which is interposed a coacting idler 24.

Above and parallel with the rollers 20 is a slotted plate 25, whose lower end is secured to a bracket 26 on the frame 10, in which the lower ends of rollers 20 and 21 are journaled. The plane top surface of this plate is substantially tangential with the upper portion of the periphery of a roller 27, journaled in the frame 10, parallel with and below the folding-rollers 7, for a purpose hereinafter appearing. Above the plate 25 is a similar plate 25^a, whose lower edge is also secured to the bracket 26 and whose upper edge is adjacent to and parallel with one of the rollers 7, and its upper plane surface is substantially tangential to the lower portion of the periphery of the other of the rollers 7, as shown in Figs. 3 and 6.

The portion of the sheet folded by the rollers 6 is conveyed over and upon the inclined plate 25 and the portion folded by rollers 7 over and upon the similar superposed plate 25^a in the following manner: Carrying-tapes 28 run over one of the rollers 6 and under the other of said rollers, thence over the roller 27 and return around idlers 29, journaled in a suitably-located bracket 30 on the frame 10. Another set of carrying-tapes 31 passes around one of the rollers 7, downwardly adjacent to the plate 25^a, under idlers 32, over and around idlers 33, thence upwardly above plates 25, around idler-pulleys 34, journaled in brackets 35 on the frame 10, then over the roller 27, and downwardly adjacent to the upper surface of plate 25, returning over idler-pulleys 36 to the said roller 7. The idler-pulleys 32, 33, and 36 are journaled in an adjustable bracket 37 on the frame 10, as below explained. Thus the portion of the sheet folded by rollers 6 is advanced by tapes 28 until its forward edge comes between the latter and the under surface of the portion of tapes 31, adjacent to plate 25. The latter tapes thereupon deflect the said contiguous portion of the sheet downwardly, maintaining the same in contact with the upper surface of the plate. The portion of the sheet folded by rollers 7 is carried downwardly between the plate 25^a and the proximate portion of tapes 31. When the said folded sheets are thus carried positively down said inclined plates, the sheets are suitably stopped along their forward edges by a stop-bar 38, which is bifurcated or slotted, as seen in Figs. 7 and 8, one of its members being above and adjacent to the surface of plate 25 and the other above and adjacent to the companion plate 25^a. The said stop-bar 38 is suitably carried by a frame 39, which is adjustably mounted on the frame 10, as hereinafter described. Projecting inwardly from the stop-bar above the plates 25 25^a, respectively, are flanges 40, (seen in Figs. 7 and 9,) having longitudinal guideways 41 in their under surfaces adjacent to the respective plates, in which guideways are fitted and adapted to slide rods or bars 42. The outer ends of these bars or rods are secured (in this instance adjustably, as hereinafter set forth) to a block 43, which is pivoted in the yoke-shaped lower portion of an arm 44, projecting from the inner end of a sleeve 45 on a shaft 46, mounted between arms or extensions 47 of the frame 39. Depending from the sleeve 45 is an arm 48, on the lower or free end of which is a roller 49, that rides against a cam 50 on a shaft 51, journaled in the frame 10, parallel with the rollers 20 21. The roller 49 is held in operative contact with the cam through the action of a spring 52, which, encircling a rod 53 on an upwardly-extending arm 54 on the sleeve, acts against a collar on said rod and against a suitably-disposed lug or shoulder 55, through which the rod extends. The cam-shaft 51 is driven from the rollers 21 through suitably-arranged coacting gear-wheels 56. The speed of rotation of shaft 51 and the cam 50 thereon is so timed that while the sheets are being carried to their position against the stop-bar 38 (between the respective portions of tapes 31 and the plates 25 and 25^a) the roller 49 will be on one of the high faces of the cam, and hence the bars 42 will be retracted against the stress of the spring 52, and after the sheets have been alined along the plane edge of the stop-bar the roller 49 will descend into one of the depressions of said cam and so permit the spring to press outwardly arm 54, thus per-

force moving the bars longitudinally toward the adjacent edge of the sheets overlying plates 25 and 25^a and pushing the sheets along the stop-bar to a certain fixed and definite position of adjustment regulated by the depth of the impression in the cam. It will be observed that the lower portions of the flanges 40 are beveled or inclined to present to the upper surfaces of the folded sheets as they are moved against the stop-bar thin edges 40^a, which hold the folded portions of each sheet in close contact with each other, so as to insure their uniform engagement by the push-bar and to obviate all liability of the buckling or bending of the paper when acted upon by said bar. When the sheets have been adjusted, as above stated, the usual folding-blade 57 descends and tucks the one upon the

plate 25^a within the one upon plate 25 and the two into the bite of folding-rollers 20, by which they are again and finally folded. This folding-blade is carried by an arm 58, projecting upwardly from a shaft 59, journaled in frame 10, parallel to and above shaft 51. An arm 60, depending from shaft 59, carries at its free end a roller 61, which impinges against a cam 62 on the shaft 51, which cam in its rotation effects the actuation of the folding-blade to tuck the sheets into the bite of rollers 20, in well-known manner.

Supported in the yoke-shaped lower end of the frame 10 is the usual vertically-adjustable packing-trough 63. In this instance the trough is supported upon vertical threaded rods 64, passing through nuts 65, held in the frame. These nuts are connected by a chain 66, geared with sprocket-wheels 67 on said nuts, one of the latter being provided with a hand-wheel 68, which when rotated turns the nuts and effects thereby the raising or lowering of the packing-trough, as may be desired. The sheets folded by rollers 20 pass between rollers 21 and are discharged thereby into the packing-trough, where they are packed in the usual way. The latter rollers insure a closer fold of the sheets as they pass therebetween.

In order that the frame 10 may be adjusted laterally across the machine to bring the rollers 7 nearer to or farther from the rollers 6, as may be required to suit different size sheets to be folded without affecting the working of the other parts of the machine, I employ the following mechanism: The frame 10 is provided at its upper end at its respective sides with lugs or brackets 69, that fit over and slide longitudinally along a trackway consisting of T-rails 70, secured to the main frame and extending across the machine in a plane at right angles to the axes of the rollers 6 and 7. Journaled in bearings in the main frame in parallelism with said rails are two horizontal shafts 71, which are provided with similarly-threaded portions 72, fitted to internally-threaded lugs 73 on the frame 10. On said shaft are suitably located bevel-gears 74, which engage like gears 75 on a transverse shaft 76, having its bearings in the main frame, the latter shaft being provided with a crank 77 for rotating the same. If this crank be properly turned, the shaft 71 will be rotated and the threaded lugs 73 thereon will be moved in either direction along said shafts, thus sliding the frame 10 and the parts carried thereby toward or away from the rollers 6, as desired. The cam 19 is so mounted on the shaft 16 and connected with the said frame as to partake of the adjustments of the latter, and thereby remain in engagement with the roller on the lower end of the arm 18—that is to say, the cam is splined on a sleeve 78 on the shaft and is connected by means of a yoke 79 with the frame 10. This spline is, as usual, spirally set in order to insure the requisite timing of the cam in re-

spect to its co-operating parts, when said cam is longitudinally adjusted on its shaft, as just described. The gear 11, previously referred to, is mounted on its shaft 2 correspondingly with the cam 19, so as likewise to partake of the adjustments of the frame 10, the yoke connection being indicated at 80. Inasmuch as the rollers 29 and roller 27 over which pass the tapes 28 are carried by the frame 10 these tapes will remain taut at any position of adjustment of said frame.

As it is desirable that the stop-bar 38, together with the side pusher-bars 42 and the mechanism for actuating the latter may be adjustable along plates 25 25^a, parallel with the path of movement of the incoming sheets to suit smaller or larger sheets to be folded, the frame 39 upon which said stop-bar, &c., are mounted has a dovetailed base 81, which rests in and is adapted to slide longitudinally in a correspondingly-grooved trackway in a lug 82, secured to frame 10. Said lug is tapped for the reception of the threaded shaft 83, whose outer end is journaled in a lug 84 of the frame 39 and is provided with a hand-wheel 85, whereby said shaft may be rotated and the frame 39 thereby adjusted along the guideway 82. In order that the roller 49 may remain in contact with the cam 50, I make the said cam with a broad face, as seen in Figs. 1 and 6, so that the roller may move along the same when the frame 39 is adjusted, as just described. The stop-bar 38 is slotted at 86, as seen in Fig. 5, to permit the folding-blade to reciprocate therein at any position of adjustment of the said bar.

As it is desirable that the side adjusting-bars 42 may be longitudinally adjustable in their respective guideways 41, I secure the said rods to the block 43 in such manner that they may be independently so adjusted. To this end the block 43 is provided in its upper and lower surfaces, respectively, with longitudinal dovetailed grooves, in which are adapted to slide the outer dovetailed ends 42^a of said bars. Each of these bars has at its outer end a lug 87, in which is mounted a thumb-screw 88, whose inner or threaded end is screwed into the body of the block 43. By properly turning the thumb-screws, or either of them, the bars 42, or either of them, may be adjusted upon the block 43, and thereby the extent of inward reciprocation of the bars 42 by the action of the spring and cam may be nicely regulated.

It is sometimes desirable to slightly adjust the stop-bar 38 in a plane parallel with the incoming sheets to true the forward edges of the latter. I therefore pivot the stop-bar at one end to the frame 39 by means of a pin 89, and at some distance forward of the pivot I provide oppositely-disposed adjusting thumb-screws 90, which pierce threaded lugs 91 of the stop-bar and bear against the opposite sides of a downwardly-projecting lug 92 on the frame. To adjust the stop-bar 38 in either direction, one of said thumb-screws is

turned to retract its inner end from the lug 92, and the other screw being screwed up pushes and so adjusts the bar on its pivot until the inner end of the opposing screw 5 again impinges against lug 92. This latter adjustment is so slight that it does not materially interfere with the reciprocations of the bars 42 in their guideways in the bar 38.

I claim—

- 10 1. In a folding-machine, the combination with the main frame, a set of horizontal folding-rollers therein, and means for rotating said rollers, of a frame adjustable toward and from said rollers, horizontal folding-rollers mounted in said frame, a set of inclined rollers also mounted in said frame, means for concertedly actuating said horizontal and inclined rollers, carrying-tapes leading from the first-named set of horizontal rollers to the second set, guide-rollers for said tapes on the adjustable frame, carrying - tapes extending from the latter set of rollers adjacent to and parallel with the inclined folding - rollers, guide-rollers for said latter tapes on the said adjustable frame, and means for bodily adjusting said frame, substantially as described.

2. In a folding-machine, the combination with the inclined folding - rollers and their supporting and operating parts, of a guide or supporting plate above and adjacent to said rollers, means whereby a previously-folded sheet is fed onto said plate, a stop or abutment bar on said plate, a push-rod, means whereby it is caused to act against the edge 35 of the sheet to adjust the same, and means whereby the sheet is delivered to the said rollers and folded thereby, together with means for adjusting said stop-bar and push-rod in a direction parallel with the movement 40 of the incoming sheet, substantially as described.

3. In a folding-machine, the combination with the final folding-rollers and their supporting and operating parts, of a guide-plate supported above and adjacent to said rollers, means whereby a previously-folded sheet is fed onto said plate, a side stop-bar for said sheet, a frictional device adjacent to said bar adapted to act on the upper edge of the sheet, 45 a push device adapted to act upon the edge of the sheet and push the same to a prescribed position of adjustment, and means whereby the sheet is delivered to said rollers and folded thereby, substantially as described.

4. In a folding-machine, the combination with the final folding-rollers, and their supporting and operating parts, of a guide-plate supported above and adjacent to said rollers, 50 means whereby a previously-folded sheet is fed onto said plate, a stop-bar, a frame on which it is pivotally mounted, means whereby said bar may be fixed in positions of lateral adjustment, a push-bar adapted to slide 55 upon said plate and act against the edge of the sheet, mechanism supported by said frame

for reciprocating said bar, a support for said frame, means for bodily adjusting the latter, and means for actuating said reciprocating mechanism, together with means whereby the sheet is delivered to said rollers and folded thereby, substantially as described.

5. In a folding-machine, the combination with the final folding-rollers and their supporting and operating parts, of two parallel guides or supports arranged above and adjacent to said rollers, means whereby previously-folded sheets are fed onto the respective guides, a common stop-bar for the sheets on said guides or supports, the block provided with dovetail grooves, the push-rods whose outer ends are provided with dovetails engaging said grooves, the lugs on said rods, the thumb-screws passing through said lugs and into said block for adjusting the relative positions of said push-rods to said block, means for reciprocating said block and rods to adjust the sheet laterally upon said guides, and means whereby said sheets are delivered to the said rollers and folded thereby, substantially as described.

6. In a folding-machine, the combination with the final folding-rollers, and their supporting and operating parts, of two parallel guides or supports arranged above and adjacent to said rollers, means whereby previously-folded sheets are fed onto the respective guides, a common stop-bar for the sheets on said guides or supports provided with laterally - projecting flanges or projections against which the upper surfaces of the sheets on said guides are adapted to impinge, and push-rods movable upon the respective guides or supports and adjacent to said flanges or projections, and means whereby said sheets are delivered to said rollers and folded thereby, substantially as described.

7. In a folding-machine, the combination with the main frame, of a frame adjustably mounted thereon, the final folding - rollers mounted at an angle or inclination on said latter frame, means for operating said rollers, means whereby previously-folded sheets are fed above said rollers, means whereby said sheets are delivered between said rollers and folded thereby, a vertically-adjustable packing-trough mounted on said frame below and adjacent to said rollers and adapted to receive the finally-folded sheets, means for horizontally adjusting said frame, and means for vertically adjusting said trough, substantially as described.

8. In a folding-machine, the combination with the main frame, of a frame adjustably mounted thereon, the final folding - rollers mounted at an angle or inclination on said latter frame, means for operating said rollers, means whereby previously-folded sheets are fed above said rollers, means on said adjustable frame for side-guiding and adjusting the sheets in respect to the rollers, means whereby said sheets are delivered between

said rollers and folded thereby, a vertically-adjustable packing-trough mounted on said frame below and adjacent to said rollers and adapted to receive the finally-folded sheets, 5 means for horizontally adjusting said frame, and means for vertically adjusting said trough, substantially as described.

In testimony whereof I have hereunto affixed my signature this 29th day of July, A. D. 1899.

HOWARD K. KING.
